THREAD RING GAUGE

Bernard Fishman, Brooklyn, N. Y.

Application December 7, 1944, Serial No. 567,069

1 Claim. (Cl. 33—199)

1
This invention relates to new and useful improvements in a thread ring gage.

More specifically, it is proposed to provide a thread ring gage provided with means increasing the life of the gage.

Still further, it is proposed to provide a thread ring gage having means for reducing the variation in diameter of the thread along the width of the gage as wear takes place.

Another object is to provide a thread ring gage having an unthreaded center.

Still another object is to provide a thread ring gage having a grooved center.

A further object is to provide a thread ring gage formed of three parts secured together, the two outer parts being threaded and the center part being smooth and having a larger inside diameter forming, between the threaded parts, a center groove.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a thread ring gage constructed in accordance with this invention.

Fig. 2 is an enlarged section on the line 2—2 of Fig. 1.

Fig. 3 is a view, similar to Fig. 2, of a thread ring gage constructed in accordance with a modification of this invention.

Fig. 4 is a front view of a thread ring gage constructed in accordance with a further modification of this invention.

Fig. 5 is an enlarged section on the line 5—5 of Fig. 4.

Thread ring gages of conventional well known types are threaded from one side of the gage to the other. It has been found that, from continually threading a member into the gage from opposite sides thereof that the threads are subject to wear. This wear in the diameter of the gaging surface is not uniform, however, throughout the width of the gage. In the "go" gage, the wear will be greater at the sides than at the center. In the "not go" gage, the wear will be limited to the first two or three threads in from both sides. The result of this variation in wear is that the threads in the center of the gage will be smaller in diameter than the threads at the sides. This type of gage is adjusted to compen-

sate for wear by decreasing the diameter of the ring gage, the ring being split and provided with suitable adjusting and locking mechanism for this purpose. The present invention is directed toward providing a thread ring gage in which the center threaded portion of greater diameter cannot form, thus greatly lengthening the life of the gage.

A thread ring gage constructed in accordance with this invention is shown in Figs. 1 and 2 and indicated generally by the reference numeral 10. This gage 10 comprises a split ring body 11, the split or gap 12 of which is radial. The gage is adjusted and set by means of an adjusting screw 13, sleeve 14, and locking screw 15. The gage also has one or two adjusting slots 21 and adjusting slot terminal holes 23. The ring gage has an axial bore 16, which contains the gaging threads. This bore is provided with a circumferential or annular center or inner groove 17. The bore has the gaging threads cut in marginal sections flanking the undercut channel or groove 17, the threads being indicated on one side by the numeral 18 and on the other by the numeral 19.

2
The operation of the device is as follows:

When the ring gage is new, the threads 18 and 19 are of the same diameter. In use, the gage may be employed from either side, depending upon the convenience of the user. After extensive use, however, the threads 18 and 19 tend to wear and increase in diameter. Such increase may be compensated for by an adjustment of the adjusting screw 13, thus restoring the gage to the correct size.

However, as the outer threads of 18 are used more than the inner threads, and as they are subjected to greater wear, the row of threads 18 tend to wear conically with the outer threads wearing the most. The same is true of the threads 19. However, due to the relatively short width of the threads 18, this conical wearing does not interfere with the accurate gaging by the ring, and the same is true of the threads 19. This is due to the groove 17 which, by eliminating center threads in the ring, separates the two sets of threads, decreases their width, and prevents any appreciable variation in the diameter of the thread along the width of the gage. This permits the extended use of the gage even though the threads 18 and 19 are wearing, and permits adjustment by the adjusting device to take up this wear. The importance of the groove 17 may be best understood if it is considered that were no groove 17 provided, then the threads 18 and

19 would meet at the center of the ring. These center threads would be used least of all the threads on the "go" gage, and not at all on the "not go" gage, and would consequently receive little or no wear but would remain their original size while the threads 18 and 19 increased in diameter.

Eventually the center threads would be of such a different diameter from the threads on either side thereof that, in adjusting the ring with a male plug gage, the user would be threading the plug gage into a cone of considerable length and would therefore not be able to get an accurate setting, the plug gage setting the ring gage according to the center unworn threads and not according to the threads (18 and 19) to be used.

A thread ring gage 10', constructed in accordance with a modification of this invention, is shown in Fig. 3. It distinguishes from the gage 10 in that, instead of having the groove 17, it has an unthreaded portion 17' which acts similarly to the groove 17. Other corresponding parts are indicated by like references with an accent added.

A thread ring gage 10'' constructed in accordance with a further modification of this invention, is shown in Figs. 4 and 5. As a finished ring, it performs similarly to the ring 10. It distinguishes therefrom in that the threads 18'' are in a ring member 18^a, the threads 19'' are in a ring member 19^a and the groove 17'' is formed by a washer 17^a of larger inside diameter than the members 18^a, 19^a. The members 18^a, 19^a and washers 17^a are secured together by countersunk screws 22 and dowels or by any other suitable manner.

It is to be understood that the cross sectional shape and width of the annular groove 17 may be varied as desired.

While I have illustrated and described the preferred embodiments of my invention, it is to

be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A thread ring gauge, comprising a pair of identical split rings having precision internal screw threads of a constant pitch and continuous helix, a split ring disposed between the two rings and having an internal diameter considerably greater than the internal diameter of the two rings first named, screws connecting the rings in concentric relation to each other, the rings having radial slots registering with each other and located between the screws, and male and female screws extending through the last-named split ring to constrict or expand the diameter of the first-named split rings, the thickness of the last-named split ring being no greater than the thickness of the first-mentioned split rings and its internal wall surface being concentrically spaced from engagement with a screw to be checked by the ring gauge.
